(57) **CLAIM**

The ornamental design for an endoscope connector, as shown and described.

DESCRIPTION

1. Endoscope connector

Fig. 1.1 is a front, left, and top perspective view of an endoscope connector showing my new design;

Fig. 1.2 is a rear, right, and top perspective view thereof;

Fig. 1.3 is a front elevation view thereof;

Fig. 1.4 is a rear elevation view thereof;

Fig. 1.5 is a left side view thereof;

Fig. 1.6 is a right side view thereof;

Fig. 1.7 is a top view thereof; and

Fig. 1.8 is a bottom view thereof.

The broken lines, and surfaces trapped within, show portions of the endoscope connector that form no part of the claimed design. The colors in the figures form no part of the claimed design.
